UNITED STATES PATENT OFFICE.

MURRAY HINCKLEY SPEAR, OF LONDON, ENGLAND.

RULING DEVICE.

SPECIFICATION forming part of Letters Patent No. 404,315, dated May 28, 1889.

Application filed April 25, 1888. Serial No. 271,842. (No model.) Patented in England March 15, 1888, No. 4,036.

To all whom it may concern:

Be it known that I, MURRAY HINCKLEY SPEAR, engineer, a subject of the Queen of England, residing at London, in England, have 5 invented certain new and useful Improvements in Ruling Devices, (for which I have received a patent in England March 15, 1888, No. 4,036;) and I do hereby declare that the following is a full, clear, and exact description 10 of the same.

Owing to the expense and trouble attending the use of the ordinary ruling-pens used by printers for ruling a number of parallel lines, an apparatus having a number of steel 15 disks, side by side, upon the same axis was devised, but has had but slight success from the fact that the steel being rigid would not accommodate itself to the paper, and would not absorb the ink; consequently the disks 20 would not carry sufficient ink to produce good lines, and printer's ink could not be used, a kind of aniline ink or dye being used instead.

Now, by experiments I have found that by 25 making the disks or rules of some substance of a different nature from steel, and which, while presenting a sufficiently rigid or inflexible surface to produce a good line, will nevertheless give sufficiently to accommodate in- 30 equalities of surface or material in the paper, and will so far absorb or "take" the ink that

a proper supply can be carried by the disk or rule, the difficulty of the steel disks may be got over and a satisfactory result obtained.

It will at once appear that various materials 35 may be used; but the best for the purpose which I have so far found is vulcanized fiber, made sufficiently firm and solid not to give too much while the lines are being ruled, but sufficiently fibrous to take or "hold" the 40 printer's ink, which simple india-rubber will not do.

Having now particularly described and ascertained the nature of my said invention and in what manner the same is to be per- 45 formed, I declare that what I claim is—

A disk for ruling purposes adapted to carry the marking compound, made of vulcanized fiber or equivalent material which is sufficiently fibrous to take the marking compound, 50 and firm enough to form the perfect edge to give the impression to form the line, substantially as described.

In testimony whereof I have hereunto set my hand in the presence of the two subscrib- 55 ing witnesses.

MURRAY HINCKLEY SPEAR.
